DUPLICATOR

Albin B. Wahlquist, and Otto De Cardy, Chicago, Ill., assignors to The Heyer Corporation, a corporation of Illinois

Application October 21, 1936, Serial No. 106,722

6 Claims. (Cl. 101—131)

This invention relates to duplicators and more particularly to that part thereof relating to the means of holding and locking the gelatin sheet taut and the combination of securely attaching the duplicator to any convenient flat surface.

Duplicating machines are composed of an oblong base, usually with a felt covering thereon, a gelatin sheet to which ink is applied, and means for stretching and holding the gelatin sheet taut. 10 The master sheet, of which copies are to be made, is placed upon the gelatin sheet in order to impart to the sheet the printed matter appearing on the master sheet. Thereupon plain sheets are successively pressed against the gelatin sheet to receive an imprint and thereafter are removed. 15 The gelatin sheet, being markedly adhesive, tends to be drawn away from the board to which it is attached unless it is securely affixed or locked in some suitable manner.

Various devices have heretofore been used for holding the gelatin sheet taut and for locking the same, but as to the latter all the methods employed have been unsatisfactory either in that the adhesiveness was too great so as to pull the 20 gelatin sheet away from the duplicator board, or it was necessary to have a locking device which was cumbersome and expensive.

It is therefore an object of our invention to produce a duplicator which will hold the gelatin sheet and the like taut, and which will securely and unquestionably lock the same and prevent the gelatin sheet becoming removed from the duplicator board.

A further object is to provide the aforesaid locking means in a simple manner which does not even require any screw or frictional contact and which will not be cumbersome to operate and which will be very inexpensive to manufacture.

40 A further object is to provide means for quickly and readily securing said duplicator to any flat surface, horizontal or vertical, which will have sufficient strength to overcome the pronounced adhesive tendency of the sheets as they receive the imprint from severing the contact between the duplicator board and the surface to which it is applied.

These and other objects will more readily appear from the drawing in the light of the following specification, in which drawing:

Fig. 1 is a plan view of our improved duplicator.

Fig. 2 is a side elevation of the same showing in full lines the locking device in fixed or operative position, and in dotted lines in a raised position.

Fig. 3 is a perspective view of the gelatin sheet.

Fig. 4 is an enlarged elevational view of the tensioning and locking mechanism.

Fig. 5 is an elevational view taken on the corner edge of the duplicator with the tensioning 5 and locking device in raised position.

Fig. 6 is a corner and elevational view of the duplicator with the gelatin sheet in position.

Like characters are applied to similar parts in each of the respective drawings, in which 1 is the 10 base or board of the duplicator, made of wood or metal, said base normally having a covering of felt or similar material not shown on the drawing; 2 is the gelatin sheet; 3 is the substantially U-shaped metal edge to which the gelatin sheet 15 is attached for cooperative contact with the lateral flange 4 on the end of the duplicator board; 5 is a bar for cooperative contact with the U-shaped metal edge 6 of the gelatin sheet; 7 is the side-piece of the tensioning and locking device secured to the duplicator board by the screw 8; 9 is a pin serving to limit the downward direction of the toggle arms; 10 is a slot in the side-piece 7; 11 is an aperture in one arm of the toggle; 12 is the end of the bar 5 journaled in the aperture 11; 13 is one arm of the toggle arm journaled at 14 to the other arm 15, which arm is in turn journaled to the side piece 7 and the duplicator board 1 at 16 by means of the screw 17; 18 is a knob attached to the journal 14; 19 20 is the channel formed by the U-shaped member 6; 20 is the similar channel formed by the edge 3; 21 is the metal plate remote from the tensioning and locking mechanism secured to the end of the board 1 by means of the screw 22; 23 25 are rubber suction cups attached to the duplicator board by means of the screws 24; 25 are the concave ears of said cup; and 26 is a recess in the interior of said cups.

The device functions in the following manner: 40 The gelatin sheet (Fig. 3) is first hooked over the edge remote from the tensioning and locking mechanism, as shown in Fig. 6, by having the lateral flange 4 engage the channel member 20 of the metal edge 3. Thereupon the channel member 19 of the metal edge 6 is engaged by the bar 5 within said channel member, the tensioning and locking mechanism being in raised or inoperative position as shown in Fig. 4. Thereupon the tensioning and locking mechanism is pressed downward by means of the knob 18. 45 Since the toggle arm 15 is fixed stationary by means of being journaled at 16 to the side of the duplicator base, the toggle arm 13 when the knob 18 is pressed downward tends to move outwardly 50 55

in the slot 10 of the sidepiece 1. This action tends to tension the gelatin sheet 2 and holds it taut on the base 1. The downward direction as pressure is applied to the knob 18 is arrested by the pin 9, which is carefully located at the point so that when the toggle arms come in contact therewith, the alignment of said arms causes an angle slightly less than 180 degrees. This produces a bracing or counteracting effect when the adhesive 5 tendency of the gelatin sheet tends to exert a pull tending to loosen the gelatin sheet. In practice it has been found that this locking mechanism is very effective and will hold the gelatin sheet taut in locked position until pressure is applied by hand on the knob 18 for the purpose 10 of disengaging the locking effect. If the pin 9 were positioned in such manner that the angle of the toggle arms was 180 degrees rather than somewhat less, the tension of the gelatin sheet 15 2 would be relaxed to such an extent as to make the locking device inoperative.

The adhesive tendency of the gelatin sheet to stick to the sheets being applied thereto is quite pronounced so that of necessity the duplicator 20 base must be securely affixed to some horizontal or vertical surface. While this could be done permanently by means of screws or nails, yet these duplicator bases are very commonly used on desks and in the school room; consequently 25 fastening the same by means of screws or nails is out of the question. We have therefore utilized a compound rubber suction cup of concave shape as shown in Fig. 2, having a further recess 26 which when the board is firmly pressed or thrown 30 forcibly against a flat surface tends to eliminate any air between the inside of the cup and the flat surface. Then when the tension or force is removed, the cup being made of rubber having a comparatively strong tension, a tendency towards 35 40 a vacuum is created which will securely affix the duplicator board to the flat surface. This suction adhesion is tremendously intensified by means of the recess 26 which tends to form a vacuum within a vacuum with the result that 45 the adhesive connection between the duplicator board and the flat surface to which it is attached is very pronounced. Obviously this strong adhesive tendency is very useful and necessary when used in combination for printing duplicate sheets. 50 Furthermore, these suction cups also serve the further purpose of serving as a cushion whereby the imprint is decidedly enhanced.

Having thus described our invention, what we 55 claim is new and desire to secure by Letters Patent is:

1. A portable duplicator comprising a base, means for connecting thereto a gelatin sheet and the like, and a toggle mechanism for stretching said sheet situated intermediate the ends of 60 said base, said toggle mechanism being capable of extending its opposing arms beyond a straight line whereby a locking action is obtained.

2. In a device of the class described, a board having an edge at one end thereof for cooperative 65 engagement with a U-shaped trough or channel

attached to a gelatin sheet, an edge at the other end of said board for similar engagement with a similar U-shaped trough at the other end of said gelatin sheet, said last named edge or bar having cooperative connection with one arm of a toggle mechanism, said mechanism adapted to press said gelatin sheet exteriorly when force or pressure is exerted against said toggle mechanism. 5

3. In a device of the class described, a board 10 having an edge at one end thereof for cooperative engagement with a U-shaped trough or channel attached to a gelatin sheet, an edge at the other end of said board for similar engagement with a similar U-shaped trough at the other end of 15 said gelatin sheet, said last named edge or bar having cooperative connection with one arm of a toggle mechanism, said mechanism adapted to press said gelatin sheet exteriorly when force or pressure is exerted against said toggle mechanism, and a pin located on the side of said board directly in the path of the arms of said toggle mechanism, the said pin being positioned below a horizontal line drawn between the extremities 20 of the two arms of said toggle mechanism in extended position.

4. In a device of the class described requiring no separate table or base or separate attaching means, means for connecting thereto a gelatin sheet, and a toggle mechanism consisting of two 30 arms pivoted together at one end of said arms, the second end of one arm pivotally connected to the side of said base and the other end of the second arm movably mounted in a slot at the side of said base for the purpose of stretching said sheet, said toggle mechanism situated intermediate the ends of said base. 35

5. In a duplicator the combination of a base 40 made integral with said duplicator and requiring no supporting table or attaching means, a gelatin sheet and a toggle mechanism for stretching said sheet, said toggle means supported by and attached to said base and situated intermediate the ends thereof and comprising two arms pivoted together at one end of each of said arms, the other end of one of said arms being pivoted at a fixed place in the side of said base and the other end of the second arm adapted for sliding action in a slot in the side of said base. 45

6. In combination a duplicator consisting of a base made integral therewith, a gelatin sheet, means for removably attaching one end of said gelatin sheet to one end of said base, a pair of toggle mechanisms situated on the side of said base intermediate the ends thereof comprising two arms pivotally connected, the other end of one arm pivotally journaled to one side of said base, the other end of said second arm pivotally connected to a bar extending transversely of said base, said bar adapted to receive the other end of said gelatin sheet and adapted for longitudinal movement in a slot at each side of said base. 50 55 60
